Fig. 2.

UNITED STATES PATENT OFFICE

FRITZ JOHNSON, OF RACINE, WISCONSIN, ASSIGNOR, BY MESNE ASSIGNMENTS, TO STEPHENSON UNDERWEAR MILLS, OF SOUTH BEND, INDIANA, A CORPORATION

PRINTING MACHINE

Original application filed August 10, 1927, Serial No. 212,026. Divided and this application filed October 10, 1928. Serial No. 311,430.

This invention relates in general to printing machines and more particularly to a ribbon inking mechanism capable of organization and advantageous use with a printing machine of the type especially designed and adapted for printing the numbers or characters in the spaces of so-called "coupon tickets" employed for keeping a record of piece work in various industries. This application 5 is a division of the copending application of Fritz Johnson for printing machines filed August 10, 1927, Serial No. 212,026.

In a printing machine of this type, the inking ribbon overlies the printing bed during the printing operation, and the impression of the type of the bed is transferred through the ribbon to the coupon which overlies the ribbon, the impression being effected by means of a platen brought down upon the 10 coupon and pressing it toward the ribbon and bed. A guard intervenes between the coupon and ribbon and precludes any soiling or improper printing on the coupon although cut out to permit impression in the proper spaces 15 of the coupon. Printing beds of this character are usually made up of adjustable or replaceable type in order to permit the matter printed to be varied as required. The adjustment or replacement of said type requires that the printing bed be easily accessible.

One of the principal objects of the present invention is to provide a simple and practical ribbon inking mechanism which is so constructed and mounted that it may be easily brought into co-operative relation to the printing bed or moved to a position away from the printing bed to afford convenient access thereto.

Another object resides in the provision of a ribbon inking mechanism having these advantages and which is equipped with both manual and automatic feeds so that while the ribbon is automatically advanced through a predetermined and proper distance following each impression it may be also manually advanced if desired, independently of impressions. Further, the construction is such as to permit easy rewinding of the inking ribbon.

Other objects and advantages reside in cer-

tain novel features of the construction, arrangement and combination of parts which will be hereinafter more fully described and particularly pointed out in the appended claims, reference being had to the accompanying drawings forming a part of this specification, and in which:

Figure 1 is a fragmentary perspective view looking toward the front of the machine and showing the inking ribbon and its frame elevated to expose the printing bed, the printing bed being illustrated diagrammatically for the sake of simplicity in illustration;

Figure 2 is a fragmentary perspective view looking toward one side of the machine and having parts broken away in order to illustrate the means for operating the platen;

Figure 3 is a fragmentary detail view in side elevation illustrating the feed mechanism for the inking ribbon;

Figure 4 is a view in section taken on line 4—4 of Figure 3;

Figure 5 is a detail sectional view showing the construction of the pawl of the ribbon feed;

Figure 6 is a fragmentary detail sectional view showing the swingable mounting of the ribbon frame;

Figure 7 is a similar view showing tension means for the inking ribbon;

Figure 8 is a view of the ribbon frame in central longitudinal section, the ribbon being shown in elevation for the sake of simplicity of illustration; and

Figure 9 is a view in transverse section taken on line 9—9 of Figure 8.

As shown, the printing machine comprises a suitable base 1 supported on legs 2 which may be appropriately braced by means of cross members 3. On the base 1 the printing bed designated generally at B is provided. This printing bed is only partly and diagrammatically shown and may consist of a plurality of rows of adjustable printing wheels designated generally at 8. The details of construction of the printing bed form no part of the present invention and for these features reference is had to the copending application of Fritz Johnson, Serial No. 212,026, referred to above.

An inking ribbon or inking sheet 45 overlies the printing bed and is carried by a swingable ribbon frame 46 which may consist of side bars 47 maintained in spaced relation by cross rods 48. The side bars 47 are pivotally supported on the base of the machine and for this purpose one end of each side bar 47 is provided with an opening 49 which is rotatably fitted in an inwardly and laterally projecting bearing boss 50 formed on a bearing bracket 51 carried by the base of the machine as clearly shown in Figure 6. Reels or rolls 52 and 53 are provided for the inking ribbon or sheet 45, the roll 52 having a reduced extension 52^a at each end rotatably mounted in the associated bearing bracket 51, as illustrated in Figure 6. The roll or reel 53 has a reduced extension 53^a at each end rotatably fitted in the bearing opening 54 provided therefor in the associated side bar 47 of the ribbon frame (see Figure 7). The cross rods 48 also serve as fixed guides for the inking sheet or ribbon as shown in Figure 8.

Tensioning means for the ribbon is organized with the roll 53 and may consist of a friction faced shoe or washer 55 suitably fitted on one of the reduced extensions 53^a of the roll 53 and frictionally engaging the adjacent side bar 47 of the frame 46 under the influence of a compression coil spring 56 interposed between the washer 55 and a knob 57 fixed on the reduced extension 53^a and having its ends operatively associated with the washer and with the knob.

The roll 52 is intermittently driven by suitable feed mechanism which is preferably automatic. This feed mechanism comprises a ratchet wheel 58 fixed to one of the reduced extensions 52^a and a pawl 59 cooperable with the ratchet wheel 58 and carried by one of the mounting trunnions 60 of the bar 61 of a guard designated generally at 62. This bar 61 has a trunnion 60 at each end and these trunnions 60 are pivotally supported in the side bars 47 of the ribbon frame (see Figure 9).

The trunnion 60 which has the pawl 59 fixed thereto projects laterally beyond its side bar of the ribbon. The pawl 59 has a tooth 63 received in the slotted head of the pawl and pivoted thereto as at 64. The tooth 63 is projected by a spring 65 but is limited to its pivotal movement by means of a stop pin 66 which is carried by the pawl and which extends through a slightly elongated arcuate slot formed in the tooth. With this arrangement when the pawl 59 swings downwardly, that is, in a clockwise direction as viewed in Figure 3, its tooth 63 coacts with the ratchet wheel 58 to advance the inking ribbon or sheet, that is, to wind the inking ribbon or sheet on the roll 52 whereas when the pawl 59 moves upwardly, that is, in a counter-clockwise direction as viewed in Figure 3, the spring 65 is compressed to permit the

tooth 63 to play idly over the teeth of the ratchet wheel 58.

A weighted dog or detent 68 is pivotally mounted on one of the brackets 51 and normally engages the ratchet wheel 58 to prevent retrograde movement of the roll 52. When the ribbon or inking sheet is to be rewound on the roll 53, this dog or detent 68 must be manually disengaged from the ratchet wheel 58 while the knob 57 is turned.

The guard 62 has the usual guard fingers 62^a suitably cut out or shaped to expose only the proper portions of the printing bed. A retractile coil spring 69 has one end connected as at 70 to one of the bearing brackets 51 and has its opposite end connected to a bracket 72 fixed to the bar 61 of the guard whereby the spring 69 tends to normally elevate the guard 62 slightly above the printing bed. To provide for manual depression of the guard and manual actuation of the feed mechanism a pivoted finger piece 73 is mounted on one of the side bars 47 of the frame and is connected to the bracket 72 by a link or connecting rod 74.

A platen designated generally at 75 is cooperatively disposed with respect to the printing bed and overlies the same as shown in the drawings, the platen being carried by curved arms 76 which are fixed to a rock shaft 77 supported for oscillating or rocking movement in bearings 78 formed on the base. A crank arm 79 is fixed to the rock shaft 77 and has its projecting portion slotted or bifurcated and formed with registering holes 80, any aligned pair of which may receive a crank pin 81 designed to coact with shoulders 82 or 83 formed on a pitman 84 which fits in the slot provided by the bifurcated arm of the crank and which is pivotally connected at its lower end to a treadle 85. The pitman 84 is biased to cause its shoulders to swing toward and engage the crank pin 81, this biasing being effected by a retractile coil spring 86 (see Fig. 2) which has one end anchored on the base of the machine as at 86^a and which has its other end connected to the pitman 84 as indicated at 87. The treadle 85 and consequently the pitman 84, the crank arm 79, the rock shaft 77, the arms 76, and the platen 75, are urged to a position wherein the platen is elevated and this action is brought about by a pair of retractile coil springs 88 connected as at 89 to the treadle and carried by a cross head 90 formed in the lower end of an adjustable mounting rod 91, the mounting rod 91 being suitably supported on the base of the machine. The platen 75 and the parts which carry the same have considerable weight and it is this weight that is utilized to make the impression, the depression of the treadle merely relieving the platen of the supporting action of the springs 88 exerted through the pitman 84, crank pin 81, rock shaft 77, and arms 76. By providing

100

130

the two shoulders 82 and 83 to coact with the crank pin 81, the platen may be cooperatively disposed with respect to the printing bed (when its shoulder 83 is engaged with the pin 81) or may be swung upwardly therefrom to permit the ribbon frame to be raised to expose the printing bed (when its shoulder is engaged with the pin 81). When the platen 75 is elevated in this manner, the handle portion 84^a of the pitman is grasped and the pitman is pushed rearwardly. The treadle 85 is held against upward movement and the platen is grasped and pushed up until the shoulder 82 is positioned beneath the pin 81 whereupon the pitman, platen and treadle are released and the platen is held elevated in the position shown in Figure 2.

Upon elevation of the ribbon carrying frame, the entire printing bed is exposed and any adjustments that may be necessary are effected in an easy and convenient manner and under the full view of the operator.

After lowering of the inking ribbon, the platen may be brought into cooperative relation to the printing bed by grasping handle portion 84^a of pitman and pressing same rearwardly to disengage shoulder 82 from pin 81 and letting platen down until the pin 81 engages the shoulder 83.

During the operation of the machine the inking ribbon is automatically fed a slight amount in between each printing operation. When the platen 75 moves down to make an impression, it rotates the guard 62 in a counter-clockwise direction as viewed in Figure 2 and similarly moves the pawl 59 (see Figure 3). This causes the tooth 63 of the pawl to play idly and upwardly over the teeth of the ratchet wheel 58. The shifting of the guard 62 tensions its spring 69 and as soon as the platen 75 is moved upwardly the spring 69 pulls the guard upwardly and this moves the pawl 59 in a clockwise direction as viewed in Figure 3 and causes its tooth 63 to move downwardly and consequently to actuate the ratchet wheel 59 to a slight extent. The spring 69 is positioned and designed to impart movement of the proper amplitude to these parts. While the guard is automatically actuated by the platen, it is free thereof and does not interfere with the platen being moved to either of its two positions.

The invention claimed is:

1. A printing machine having a printing bed, an inking ribbon overlying the printing bed, a frame for the inking ribbon, rolls upon which the ribbon is wound said rolls being rotatably mounted on the ribbon frame, tensioning means associated with one roll, feeding means associated with the other roll and including a ratchet wheel connected with the axis of such roll and rotatable therewith, a pawl cooperable with the ratchet wheel, and a shiftable guard mounted on

the ribbon frame and connected with the pawl for actuating the same.

2. A printing machine of the character described comprising a printing bed, an inking ribbon overlying the printing bed, a ribbon frame having rolls carrying the ribbon and guides therefor, means for swingably supporting the ribbon frame, feed mechanism coacting with one of the rolls for rotating it to advance the ribbon, a shiftable guard mounted on the ribbon frame above the inking ribbon and operatively connected with the feed mechanism for actuating the same when it is shifted, and a platen cooperable with the printing bed and also engaging the guard for shifting it.

3. A printing machine of the character described comprising a printing bed, an inking ribbon therefor, feed mechanism for advancing the ribbon, a shiftable guard cooperatively disposed with respect to the ribbon and operatively connected with the feed mechanism for actuating it and a platen cooperable with the printing bed and also operating to shift the guard.

4. In a printing machine having a printing bed, a ribbon inking mechanism including an inking ribbon overlying the printing bed, a feed mechanism for advancing the ribbon, a shiftable guard cooperatively disposed with respect to the ribbon and operatively connected with the feed mechanism for actuating it when the guard is shifted, said guard being adapted to be shifted upon each impression.

5. In a printing machine having a printing bed, a ribbon inking mechanism including an inking ribbon overlying the printing bed, a feed mechanism for advancing the ribbon, a shiftable guard cooperatively disposed with respect to the ribbon and operatively connected with the feed mechanism for actuating it when the guard is shifted, said guard being adapted to be shifted upon each impression, and means for manually actuating the guard for advancing the ribbon independently of impressions.

6. A printing machine of the character described comprising a printing bed, an inking ribbon overlying the bed, a swingable ribbon carrying frame, a platen mounted to be positioned to cooperate with the printing bed and also to be swung away from the printing bed to permit the swinging ribbon frame to swing up to give access to the printing bed, feeding mechanism for the inking ribbon, and operating means for the feeding mechanism disconnected from the platen to leave the same free for adjustment to its two positions but engaged and automatically actuated when the platen is operated for making an impression.

7. In a printing machine, a printing bed, an inking ribbon overlying the same, a platen cooperable therewith, feeding mechanism for the inking ribbon, operating means for the feeding mechanism, and means for moving

the operating mechanism to a predetermined extent in one direction said operating mechanism being free of the platen but being actuated thereby in one direction when the platen is moved to make an impression.

8. A printing machine of the character described comprising a printing bed, an inking ribbon overlying the printing bed, a swingable frame carrying the ribbon and positionable to operatively dispose the ribbon with respect to the bed or to position the ribbon well above the bed to permit of access thereto, a platen supported independently of said swingable frame and adapted to be cooperatively disposed with respect to the printing bed and also adapted to be swung away from the printing bed to permit access thereto and means for operating the platen and for releasably supporting it in either of its two positions.

In witness whereof, I hereto affix my signature.

FRITZ JOHNSON.
